UNITED STATES PATENT OFFICE.

WADE HAMPTON SAUNDERS, OF ROANOKE, VIRGINIA.

GARMENT-BUTTON.

1,065,082.

Specification of Letters Patent. Patented June 17, 1913.

Application filed April 29, 1912. Serial No. 693,995.

To all whom it may concern:

Be it known that I, WADE H. SAUNDERS, a citizen of the United States, residing at Roanoke, in the county of Roanoke and State of Virginia, have invented a new and useful Garment-Button; and I do hereby declare the following to be a full, clear, and exact description of the invention, such as will enable others skilled in the art to which it appertains to make and use the same.

This invention relates to a new and useful button adapted for use in connection with wearing apparel, and particularly to new and useful means for attaching the button to a garment.

It is the principal object of the invention to provide a device of this nature, in which desirable and practical features of construction exist.

20 The main features of construction is the provision of an annular recess or groove formed in the wall of a perforation in the center of the button, to receive the diverging ends of a cotter or staple pin, which is adapted to be inserted through an opening of the button and arranged transversely thereof.

30 The invention comprises further features and combination of parts, as hereinafter set forth, shown in the drawings and claimed.

In the drawings: Figure 1 is a view showing the application of the improved button and connecting means. Fig. 2 is a sectional view on line 2-2 of Fig. 1. Fig. 3 is a sectional view on line 3-3 of Fig. 2. Fig. 4 is a bottom plan view of the button.

Referring to the drawings 1 designates a section of fabric or a portion of a wearing apparel, while 2 denotes the improved button, which may be constructed in any desired shape, or provided with any desired configuration, just so long as the same is constructed with a central perforation or opening 3, in the wall of which an annular

recess or groove 4 is formed. An opening 6 is formed in the button, at right angles to the perforation or opening 3, which is adapted to receive a cotter or staple pin 7, which when received penetrates a fold 8 in the fabric or garment, in order to secure the button to the fabric. The two arms 9 of the pin diverge outwardly, in order to prevent the pin from pulling from the fold of the fabric, while the extremities 10 of the diverging arms are received in the annular recess or groove 4, thereby resisting the strain and pull exerted upon the pin by the fold of the fabric, when causing the button to enter the button-hole (not shown).

From the foregoing it will be observed there has been devised an essential and improved button and attaching means therefore, and one which has been found desirable and practicable.

The invention having been set forth, what is claimed as new and useful is:—

In combination, a garment button comprising an annular body having a central unobstructed perforation or opening extending entirely therethrough adapted to receive a fold or loop in a piece of fabric, the wall of the opening or perforation having an annular groove, the body having a second opening at right angles to the first opening and communicating with said opening and groove, an attaching means, adapted to enter the second opening and penetrate the fold or loop of the fabric and enter that portion of the groove opposite the second opening for securing the button to the garment.

In testimony whereof I have signed my name to this specification in the presence of two subscribing witnesses.

WADE HAMPTON SAUNDERS.
